WRITING PLATEN FOR LEDGER BOOKS
Hyman Brechner, 65 Bella Vista Road,
Tuckahoe, N.Y. 10707
Filed May 26, 1965, Ser. No. 458,877
3 Claims. (Cl. 129—21)

This invention relates to payroll systems and more particularly to payroll systems which use loose-leaf ledger books having journal sheets and wherein a removable writing platen may be placed below any journal sheet for securing a plurality of payroll checks with respect thereto for making entries which register line for line between shingled checks and the ruled lines on the journal sheets.

Payroll systems as generally described above are well known, as are writing platens having peg strips for holding checks or other papers which are to be shifted in line register with relatively stationary sheets.

Various prior art patents show arrangements for achieving slidable securement of peg strips on writing platens, but such known constructions are of a relatively complex nature, and are expensive to manufacture as well as having separate moving parts such as springs, clips, etc., which may become defective.

It is an object of the present invention to provide a writing platen for the purpose intended which is of exceedingly simple and rugged construction having no springs, clips or other adjustable or movable components and which can perform its function conveniently and with a minimum of manipulation.

Other objects and features of the invention will be apparent from the description which follows.

Briefly, the invention comprises the provision of a groove in a writing platen and in which groove a slidably guided peg strip is carried movable therein guided by the sides of the groove. The peg strip has conventional impaling means extending upwardly therefrom and is shaped as an inverted channel having flanges extending into the groove with edges slideable on the bottom wall of the groove. Within the channel flat magnetic chambers are carried which serve to magnetize the flanges of the channel, in effect forming a flat horseshoe magnet, the edges of which are opposite magnetic poles which magnetically grip the bottom wall of the groove. Thus, the peg strip is slidably movable in the groove but magnetically secured therein and carries one or more indexing pins coacting with indexing holes in the bottom wall of the groove for effecting line for line registration of papers impaled on the peg strip with papers resting on the platen.

A detailed description of the invention now follows in conjunction with the appended drawing in which:

FIG. 1 is an exploded perspective showing a platen panel and peg strip therefor;

FIG. 2 is a section through 2—2 of FIG. 1 showing the parts assembled;

FIG. 3 is a bottom view of the peg strip;

FIG. 4 is an exploded plan view of one form of arrangement of indexing pins and holes;

FIG. 5 is a diagram illustrating another arrangement of coacting indexing pins and holes; and

FIG. 6 is a fragmentary cross section of a modified form of the invention.

Referring now to FIGS. 1, 2, and 3, the invention comprises a writing platen in the form of a flat panel 10 having bayonet slotted ears 12 for attaching the platen in a well-known manner to the rings of a loose-leaf ledger binder. In this form of the invention, it is contemplated that the platen is made of a single piece of magnetic material such as sheet steel and is formed with a groove 15 having side walls 18 and a bottom wall 22. The bottom wall 22 is formed with a series of indexing holes 25 which may be punched therethrough. A steel peg strip 30 is of

2

channel shape, having side flanges 33 disposed invertedly so that the edges 36 of the side walls are slidably engageable with the bottom walls 22. The upper wall 40 of the peg strip is of suitable transverse width so that the flanges 33 are guided by the groove walls 18, with a smooth sliding engagement. Wall 40 carries any arrangement of conventional pins or pegs 43 on which may be impaled apertured checks, sheets, or the like, in the usual manner, which are to be shifted in line-for-line register as indicated by the phantom line spacing of FIG. 1. An indexing pin 46 carried by wall 40 coacts with index holes 25 as the peg strip 30 is shifted in the groove to hold the peg strip in any position determined by the holes 25.

The rounded end of the indexing pin is sufficient to effect a camming action when the peg strip is slid. Thus, the pin will skip from hole to hole protruding sufficiently into each hole at any desired point with the peg strip remaining in place in the groove. The slight rise of the peg strip when the pin moves between holes does not in any way effect dislodgment, and there is, of course, no need to lift the peg strip for effecting sliding.

Magnetic members in the form of flat magnetized elements 50 are carried within the peg strip channel. Such magnetic elements may be of any suitable magnetized material, and in a commercial form of the invention a flexible magnetic strip material is usable. Such material is readily available on the open market and can be cut with no difficulty to any convenient size for setting into the channel. The edges of elements 50 preferably engage the side walls 33 of the channel which form the legs of a horseshoe magnet with the edges 36 then effecting pole pieces. Such magnets 50 may be cemented in place or otherwise fastened, and it will be understood that they are magnetized transversely so that all north edges are at one side and all south edges at the other. As a practical matter, tight engagement between the edges of the magnetic members with the channel walls is not essential for effecting a strong magnetic attraction between the peg strip and the bottom wall 22 when the peg strip is placed in the groove.

It will be appreciated that the entire length of the peg strip channel may have a continuous piece of magnetic material therein but it has been found in a practical construction that only three or four of such pieces, spaced from each other, need be used.

It will also be appreciated that the peg strip could be of molded plastic with integrally molded pegs and that the magnetic members cemented therein could still serve to effect slidable securement between the peg strip and the platen, although it would then be disposed, preferably, to have its face engage the bottom wall of the groove. However, for maximum attracting strength, a peg strip of ferrous material forming a horseshoe magnet effects a very strong magnetic force and it will be noted that, as seen in FIG. 2, the bottom surface of the magnetic material is spaced from the upper surface of the bottom wall 22 so that a complete magnetic flux will have a path through the top and side walls of the channel and the bottom wall of the groove substantially as occurs when a horseshoe magnet is placed with its poles on a ferrous surface.

While the form of the invention described above contemplates the use of a steel platen panel, such construction is not essential inasmuch as the platen may be of aluminum, as shown in FIG. 6, having a main portion 60 and an end portion 63, spaced apart and secured together by means of a steel strip 66 flush riveted thereto to effect a groove 67.

The indexing arrangement shown in FIG. 1 is simply a single pin coacting with a series of aligned holes, as hereinabove described. However, greater versatility and economy can be effected by other arrangements. For example, FIG. 4 illustrates a pair of spaced pins 70 on the peg strip

coacting with holes 73 which will be understood to be in the bottom wall of the platen groove. The spacing between pins 70 is a multiple of spacing between the holes plus one half such spacing. Accordingly, only one pin at a time protrudes into a hole. The staggered spacing of the pins, however, permits manufacture of the platen with only half the number of holes which would otherwise be required to effect registration with lines which are double the number of holes. Obviously, when either pin is in a hole, the other pin is midway between a pair of other holes and can be shifted left or right to engage in either hole thereby giving half spacing between holes for movement of papers carried by the peg strip.

FIG. 5 shows another arrangement wherein the bottom wall of the groove is provided with two groups of holes, the innermost holes 75a and 75b being spaced from each other by a predetermined amount. The pins 78a and 78b are spaced from each other the predetermined amount less the spacing between any two holes in either group. Accordingly, only one pin at a time is engaged in a hole. Such an arrangement can provide very close indexing, dependent upon the spacing between holes. Thus, the pins 78a can coact with any of the holes to the left of hole 75a and to the right of hole 75b. Similarly, the pins 78b can coact with any of the holes to the right of hole 75b and to the left of hole 75a. The net effect is that the indexing positions are four times the number of holes in each group. It will of course be understood that the grooves are open ended whereby the peg strip in all modifications can move out beyond the edge of the platen regardless of the indexing arrangement used. The ends of the groove bottom walls may be slightly depressed as at 80 to permit ease of movement of pins in returning to the groove after going beyond the bottom wall edges.

Although the invention contemplates the use of indexing pins and holes generally as described herein, it will be understood that this is not absolutely essential. In fact, it has been found entirely practical in many instances to rely on the magnetic attraction of the peg strip with the platen for holding the peg strip in any desired position. Accordingly, the invention is not limited to requirement of additional indexing means nor, for that matter, to the use of a single peg strip on the platen. Two or more peg strips could be applied in accordance with the teaching.

Having thus described the invention, it is realized that changes may be made without departing from the spirit thereof and, therefore, it is not desired that the invention be limited to the precise illustration herein given except as set forth in the following claims.

I claim:

1. A writing platen having a groove with a bottom wall of magnetic material and said groove having sides connecting said bottom wall with said platen, a peg strip slideable in said groove, said peg strip being a U shaped channel having side flanges with edges slideable on said bottom wall, a magnetic member in said channel and slideable therewith having oppositely polarized edges adjacent respective flanges, said channel being of magnetic material whereby the edges thereof are magnetic poles to effect an attractive force holding said peg strip in said groove an indexing pin carried by said peg strip and indexing holes in said platen at the bottom of said groove for

effecting predetermined positions of said peg strip therein, said pin being engageable in a selected indexing hole as said channel is slidably positioned in said groove.

2. A writing platen and a peg strip slideable thereon, means for slidably guiding said peg strip, two groups of indexing holes in said peg strip and a pair of indexing pins carried by said peg strip, the holes of each group being evenly spaced and the spacing between holes being the same for each group, said indexing pins being spaced apart the distance between the innermost holes of the two groups less the spacing between holes, and means for slidably and magnetically securing said peg strip to said platen, wherein either pin is insertable in a hole in either group, said latter means comprising magnet means and further comprising a U-shaped channel having side flanges polarized by said magnet means, said writing platen having a portion to which said peg strip adheres by magnetic attraction through said flanges and said platen having a deformation effecting guiding motion for said peg strip, said pins being of a length to protrude into said holes without protruding beyond the depth thereof and having rounded ends so as to cam out of said holes when said peg strip is motivated whereby the magnetic attraction between said peg strip and said platen has a resilient effect permitting said pins to yieldably move in and out of said holes.

3. A writing platen comprising a panel, a peg strip, means for slidably guiding said peg strip on said panel, magnetic means carried by said peg strip for holding said peg strip thereon, said peg strip being a U shaped channel having side flanges and said magnetic means being within said channel and having respective edges magnetically polarizing the flanges of said channel, the edges of said channel being slidably engageable with said panel and thereby effecting a magnetic attraction therewith, said platen having a magnetic portion shaped to form a guide for said peg strip and said portion having a plurality of spaced holes, said peg strip having at least one pin extending toward said platen and of a length to protrude into a selected hole without extending therebeyond and being shaped to effect a camming action out of said hole when said peg strip is moved on said platen whereby the attraction between said peg strip and said platen effects a resilient tensioning force therebetween permitting yieldable camming action of said pin in the course of sliding of said peg strip.
